UNITED STATES PATENT OFFICE.

JAMES D. CASEY, OF GLENWOOD, ALABAMA.

RAILROAD CROSSING.

Application filed October 6, 1925. Serial No. 60,835.

- The present invention relates to railroad crossings, and aims to provide a crossing having a series of members carried by the rails for bridging certain rails according to the direction of travel of rolling stock thereover, which will present a smooth or continuous rail surface for eliminating shocks, which cause undue wear on both the rails and the wheels of the rolling stock.
- 10 Another object of the invention is the provision of a series of upstanding members pivotally connected to the ends of the rails which are adapted to be engaged by the wheels of rolling stock for swinging the same downwardly so as to bridge the ends of the rails, said upstanding members having spring means for returning the same to their normal positions after the rolling stock has passed thereover.
- 15 It is also an object of the invention to provide a device of the above indicated character, which is simple and substantial in construction, which can be manufactured economically, and which will be thoroughly efficient and practical in use.
- 20 With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.
- 25 The invention is illustrated in the accompanying drawing, wherein:
- 30 Figure 1 is a plan view of my improved crossing.
- 35 Figure 2 is a vertical section taken on line 2—2 of Figure 1, and
- 40 Figure 3 is a section taken on line 3—3 of Figure 2.
- 45 In carrying out the invention, the numeral 10 designates four sections, each composed of four small rail sections 11, which terminate at their inner ends a short distance from each other so as to permit the flanges of the wheels of rolling stock to pass in any direction over the short rail sections 11. By referring to Figure 1, it will be noted that the four sections 10 are arranged together so as to provide a railroad crossing. The inner ends of each rail section 11 is slotted, as at 12, and has pivotally received in the ends of said slots bridge members 13, the pivotal connection being provided by passing pins 14 through the sides of the rail sections and through the bridge members and having bearings 15 arranged in the sides of the rail sections for permitting the pins 14 to turn therein. The bridge members 13 are of sufficient length so that when swung outwardly from the rail sections to which the same are pivotally connected, said bridge members will extend across to the rail sections opposite thereto, and bridge 60 said sections.
- 50 Under each bridge member 13 a downwardly extending bore or opening 16 is provided in which is positioned a coil spring 17 which has its upper end attached to the 65 bridge member, while its lower end is secured to a pin 18 passing through the lower portion of the section. By providing the coil springs, the bridge members will be returned to their normal upstanding positions immediately after being disengaged by the wheels of rolling stock so as to be in the proper positions should rolling stock approach from another direction.
- 55 Arranged between the ends of the rail sections 11 are upstanding lugs 19, which are adapted to support the bridge members 13 when the same are swung thereover so that said bridge members may properly support the weight of the rolling stock passing thereover. An enlarged flange or web portion 20 is formed on each section 10 so as to properly reinforce or support the rail sections 11 against lateral movement during the passing of rolling stock thereover.
- 60 When the wheels of rolling stock approach the crossing, said wheels will engage the upstanding bridge member 13 arranged on the rail upon which the rolling stock is traveling and force said bridge member 65 downwardly and across the lug 19, said lug acting as a means for supporting said bridge member during the passing of rolling stock over the same. The wheels then engage the bridge member 13 opposite to that first engaged, forcing the same downwardly into the slot 12 arranged in the short section 11 of the rail, and thus pass the crossing without being subjected to severe shocks.
- 65 It will be noted that by providing the upstanding bridge members 13 at each end of each rail section that one of the same will bridge the gap between the rails independent of the direction of travel of the rolling stock. After the rolling stock has passed over the gap between the rails and disengaged the bridge member, said bridge member 70

ber will be swung to upright position due to the coil spring 17 attached to the same.

From the foregoing, it can be seen that I have provided a simple structure for eliminating severe shocks to rolling stock passing over a crossing, as well as a device which will also eliminate to a great extent the danger of rolling stock jumping the track at a crossing.

10 Having thus described my invention, what I claim as new is—

1. A railroad crossing comprising rail sections terminating at points adjacent each other, upstanding bridge members pivotally carried by said rails extending above the same and adapted to be swung downwardly to bridge the gap between said rails when engaged by the wheels of rolling stock.

2. A railroad crossing comprising rail sections terminating at points adjacent each other, upstanding bridge members pivotally carried by said rails extending above the same and adapted to be swung downwardly to bridge the gap between said rails when engaged by the wheels of rolling stock, and means for supporting said bridge members during the bridging of a gap.

3. A railroad crossing comprising rails terminating at points adjacent each other, upstanding bridge members pivotally carried by said rails extending above the same and adapted to be swung downwardly to bridge the gap between said rails when engaged by the wheels of rolling stock, and means for returning said upstanding bridge members to their normal positions extending above said rails after being disengaged by said wheels.

4. A railroad crossing comprising rails terminating at points adjacent each other, upstanding bridge members pivotally carried by said rails extending above the same and adapted to be swung downwardly to bridge the gap between said rails when engaged by the wheels of rolling stock, means for returning said upstanding bridge members to their normal positions after being disengaged by said wheels, and means for supporting said bridge members when bridging a gap between said rails.

5. A railroad crossing comprising rails terminating at points adjacent each other and having slots provided at their terminals, bridge members pivotally supported in said

slots and adapted to bridge the gap between the rails when engaged by the wheels of rolling stock.

6. A railroad crossing comprising rails terminating at points adjacent each other and having slots provided at their terminals, bridge members pivotally supported in said slots and adapted to bridge the gap between the rails when engaged by the wheels of rolling stock, and spring means attached to said bridge members for returning the same to their normal positions after being disengaged by said wheels.

7. A railroad crossing comprising rails terminating at points adjacent each other and having elongated slots provided in their terminals, upstanding bridge members pivotally supported in said slots, one of said bridge members being adapted to bridge the gap between the rails while the other is forced into said slot when the rolling stock approaches in one direction and vice versa when approaching in the opposite direction.

8. A railroad crossing comprising rails terminating at points adjacent each other and having elongated slots provided in their terminals, upstanding bridge members pivotally supported in said slots, one of said bridge members being adapted to bridge the gap between the rails while the other is forced into said slot when the rolling stock approaches in one direction and vice versa when approaching in the opposite direction, and means for supporting the bridge member bridging the gap.

9. A railroad crossing comprising rails terminating at points adjacent each other, bridge members pivotally carried by said rails and adapted to bridge the gap between said rails when engaged by the wheels of rolling stock, coil springs attached to said bridge members for yieldably holding the same in an upright position, means for anchoring the opposite ends of said coil springs so that said springs will normally hold said bridge members in an upright position, and an upstanding lug arranged between the terminals of said rails for supporting the bridge member bridging the gap.

In testimony whereof, I have affixed my signature.

JAMES D. CASEY.
